TURBINE APPARATUS

Seymour H. Hemenway, Swarthmore, Pa., assignor to Westinghouse Electric & Manufacturing Company, East Pittsburgh, Pa., a corporation of Pennsylvania

Application September 20, 1939, Serial No. 295,759

1 Claim. (Cl. 60—43)

My invention relates to mixed pressure turbines having high and low-pressure sections, wherein high-pressure steam is admitted to the high-pressure section for passage in series through the latter and the low-pressure section and wherein low-pressure steam is supplied to the low-pressure section, and it has for an object to provide improved means for ventilating the blading of the high-pressure section when the admission of high-pressure steam thereto is interrupted.

A mixed pressure turbine frequently should be operated so that, for any given load, the maximum possible amount of low-pressure steam is supplied to the low-pressure section in order to conserve high-pressure steam. Under certain load conditions, therefore, the steam requirements may be satisfied by the admission only of low-pressure steam to the low-pressure section, the supply of high-pressure steam to the high-pressure section of the turbine being interrupted; however, under these conditions, the blading of the high-pressure section will be overheated unless steps are taken to insure ventilation. In accordance with the present invention, a conduit is arranged between the turbine exhaust connection and the interior space of the turbine at the high-pressure side of the blading of the high-pressure section, a valve is arranged in the conduit, and the valve is controlled so as to be closed as long as high-pressure steam is supplied to the high-pressure section and to open upon the cessation of such supply. With the valve open, the conduit provides for backward flow of steam through the blading of the high-pressure section from the steam space between the high and low-pressure sections through the conduit to the exhaust connection, the steam so flowing absorbing heat from the blading and preventing the latter attaining an undesirably high temperature. Accordingly, a further object of my invention is to provide, in connection with a mixed-pressure turbine, a by-pass passage extending from the high-pressure side of the high-pressure blading to the exhaust connection and providing, when the supply of high-pressure steam is cut off, for the flow of low-pressure steam backwardly through the blading of the high-pressure section and then through the by-pass passage to ventilate such high-pressure blading.

A further object of my invention is to provide, in connection with a mixed-pressure turbine, a ventilating passage by-passing the blading of the high-pressure section and utilizing low-pressure steam flowing backwardly through the blading of the latter section when the supply of high-pressure steam is cut off in order to ventilate the high-pressure blading to prevent overheating thereof, the by-pass passage having a valve constructed and arranged to provide the flow area requisite

to secure sufficient steam for ventilating purposes.

These and other objects are effected by my invention as will be apparent from the following description and claim taken in connection with the accompanying drawing, forming a part of this application, in which:

The figure is a sectional view of a turbine incorporating the improved ventilating apparatus.

Referring to the drawing more in detail, in the figure, there is shown a mixed-pressure turbine, at 10, having an exhaust connection 11 and it includes a high-pressure section, at 12, and a low-pressure section, at 13, the high-pressure section having a high-pressure steam inlet 14 and the low-pressure section having a low-pressure steam inlet 15. As shown, the turbine has interior spaces 16 and 17 at the high-pressure and low-pressure sides of the high-pressure blading 18 of the high-pressure section and a diaphragm 19 is arranged between the space 17 and the low-pressure section.

The admission valve 20 controls the flow of steam from the high-pressure steam inlet 14 to the high-pressure section. The low-pressure steam conduit or inlet 15 is supplied from any suitable source and it preferably communicates with the interior turbine space 17, and flow from the latter through the diaphragm 19 to the low-pressure section is controlled by a valve 21. The high-pressure admission valve 20 and the low-pressure valve 21 are controlled, respectively, by servo-motors, at 22 and 23.

As shown, the turbine is provided with any suitable speed governor, at 24, having the usual speed changer apparatus including a speed changer motor 25, the governor controlling the servo-motor 22 and also, as hereinafter pointed out, exerting a controlling effect on the servo-motor, at 23. By suitable adjustment of the governor speed changer, the servo-motors are controlled so as to operate the valves 20 and 21 to utilize low-pressure steam in a preferential manner, that is, so long as the load requirements can be met by the low-pressure steam supply, the supply of high-pressure steam is cut off and the governor controls the valve 21 to admit low-pressure steam to the low-pressure section of the turbine suitably to the load requirements.

As shown, the servo-motor, at 23, in addition to being responsive to a controlling effect derived from the governor, is also influenced by the controlling effect provided by a suitable device, for example, the pressure regulator 26 associated with the exhaust connection, the arrangement being such that the exhaust steam pressure is held substantially constant with variation in the requirement for exhaust steam for any suitable purpose.

For example, the governor, at 24, is of the pres-

sure transformer type providing a liquid pressure varying as a function of the speed of the turbine. Also, the regulator 26 provides a liquid pressure which is a function of the steam pressure in the 5 exhaust connection 11. Liquid pressure provided by the governor is supplied to a passage 27 communicating with the pressure chambers 28 and 29 of the pressure-responsive devices 30 and 31 of the servo-motors, at 22 and 23, respectively. 10 The pressure-responsive device 30 includes, for example, a movable abutment 32 connected to adjacent ends of the larger and smaller bellows elements 33 and 34, the bellows elements and the annular area 35 of the abutment forming a 15 part of the boundary or enclosure of the pressure chamber 28. Likewise, the pressure-responsive device 31 includes a movable abutment 37 connected to adjacent ends of the larger and smaller bellows elements 38 and 39 so as to separate 20 the pressure chamber 29 from the pressure chamber 40, thereby providing an annular pressure area 41 exposed to pressure in the chamber 29 and the pressure area 42 exposed to pressure in the chamber 40. As already pointed out, the pressure 25 chamber 29 is shown as being supplied by liquid under governing pressure while the chamber 40 is supplied with liquid under pressure which is a function of the exhaust connection steam pressure; and, in consequence, the valve 30 31 is operated in accordance with the differential 30 effect of liquid pressures supplied to said chambers.

To avoid overheating of the blading 18 of the high-pressure section when the supply of high-pressure steam to the latter is interrupted, there 35 is provided a ventilating conduit 45 connecting the interior space 16 of the turbine at the high-pressure side of the blading 18 to the exhaust connection 11 and a valve 46 is arranged in the 40 conduit. Assuming that the supply of high-pressure steam to the high-pressure section is interrupted and that low-pressure steam is being supplied to the low-pressure section and that the valve 46 is open, then steam may flow back- 45 wardly from the interior space 17 of the turbine through the high-pressure blading 18 to the space 16, and, from the latter, through the ventilating conduit, to the exhaust connection 11, the circulation of steam so provided affording 50 ventilation of the blades 18 and preventing overheating thereof.

The valve 46 is preferably arranged for automatic operation, that is, as long as high-pressure steam is supplied to the high-pressure section, the valve is closed and it opens only when such supply is interrupted. As shown, the valve closes by movement in an upstream direction toward the space 16 and it opens in a downstream direction toward the exhaust connection 11, the 55 valve having opposed pressure areas 47 and 48 facing, respectively, in upstream and downstream directions. A movable operating member 49 is connected to the valve and it has opposed pressure areas 50 and 51 forming portions, respectively, of the boundaries of the pressure chambers 52 and 53, the pressure chamber 52 being connected by the conduits 54 and 45 to the space 16 and the chamber 53 being connected by a conduit 55 to the space 17. As long as high-pressure steam is supplied to the turbine, the pressure in the space 52 will be higher than that in space 53 to the extent of the pressure drop across the high-pressure blading 18 and the abutment 49 will be operated to close the valve 46. How- 70 ever, just as soon as the supply of high-pressure

steam is interrupted, then the pressures at opposite sides of the abutment 49 come into equilibrium; and, as the pressure of low-pressure steam is substantially higher than that of the exhaust, the differential effect thereof acting on 5 the areas 47 and 48 causes the valve 46 to open the by-pass conduit 45 to provide for backflow of steam from the section 17, through the high-pressure blading 18 to the exhaust connection 10 for ventilating such blading. When high-pressure steam is again supplied to the turbine, the pressure of steam above the abutment 49 increases and the valve 46 closes.

The valve 46 is of such size as to provide whatever throttling effect may be required to secure 15 the requisite flow of steam for ventilating purposes considering the difference in pressure of the low-pressure steam supply and that of the exhaust.

While a governor and a pressure regulator are 20 shown in operative relation to the admission valve 20 and the diaphragm valve 21, it is to be understood that these control devices are referred to only for the purpose of indicating that 25 under certain conditions the turbine is operated only by the admission of low-pressure steam to the low-pressure section, the admission of high-pressure steam to the high-pressure section being interrupted. Therefore, it is to be understood that the means herein described for 30 ventilating the blading of the high-pressure section when the supply of high-pressure steam thereto is interrupted may be used with a turbine of this 35 type irrespective of the manner in which the admission valve 20 and the diaphragm valve 21 are controlled or operated.

While I have shown my invention in but one 40 form, it will be obvious to those skilled in the art that it is not so limited, but is susceptible of various changes and modifications without departing from the spirit thereof, and I desire, therefore, that only such limitations shall be placed thereupon as are specifically set forth in the appended claim.

What I claim is:

In an elastic fluid turbine, a high-pressure section, a low-pressure section, a diaphragm separating the sections, an exhaust connection, said turbine having a first space at the high-pressure side of the blading of the high-pressure section and a second space between such blading and the diaphragm, means including an admission valve for supplying high-pressure elastic fluid to the high-pressure section, a valve for controlling the flow of steam from said second space to the low-pressure section, means for supplying low-pressure elastic fluid to said second space, means for controlling said valves, and means for ventilating the blading of the high-pressure section when the supply of high-pressure elastic fluid thereto is interrupted by closure of the admission valve; said last-named means comprising a conduit affording communication of said first space with the exhaust connection, a valve in the 65 conduit and arranged to close and to open by movements in directions, respectively, which are upstream toward said first space and downstream toward said exhaust connection, said valve having opposed pressure areas facing in upstream and downstream directions, a movable abutment 70 connected to said valve, and means providing first and second pressure chambers separated by the abutment and connected, respectively, to said first and second spaces.

SEYMOUR H. HEMENWAY. 75
